[57] CLAIM

The ornamental design for a putter head with bowed shaft, substantially as shown and described.

DESCRIPTION

FIG. 1 is a front elevation of a putter head with bowed shaft, showing my new design;

FIG. 2 is a rear elevation of the FIG. 1 putter head with bowed shaft;

FIG. 3 is a top plan view of the putter head with bowed shaft, taken on lines 3—3 of FIG. 2;

FIG. 4 is a bottom plan view of the putter head with bowed shaft, taken on lines 4—4 of FIG. 2;

FIG. 5 is a left end view of the putter head with bowed shaft, taken on lines 5—5 of FIG. 1;

FIG. 6 is a cross section taken on lines 6—6 of FIG. 1. The upper portion of the shaft is a continuation of that shown and is omitted for convenience of illustration.

FIG. 1.

FIG. 5.

FIG. 4.

FIG. 2.

FIG. 3.

FIG. 6.
